BLOWPIPE

Owen R. Rice, Chicago, Ill., assignor to Freyn
Engineering Company, Chicago, Ill., a corpora-
tion of Maine

Application March 14, 1935, Serial No. 11,005

17 Claims. (Cl. 138—63)

The present invention relates to improvements in blow pipes.

More particularly the present invention relates to pipes such as are used in connection with blast furnaces for conducting the hot blast from the bustle pipe to the tuyère. Ordinarily blow pipes used for this purpose are made of cast iron or cast steel and are not insulated, whereas the rest of the system is lined with fire brick, which has 5 certain insulating value, though in some instances the blow pipes of a blast furnace installation have also been lined with fire brick. However, a blow pipe is subjected at times to violent mechanical handling, particularly when it is 10 being moved, as for example when a tuyère is changed. Such mechanical violence dislodges the brick lining. Moreover, it happens not infrequently that molten slag and/or iron runs back 15 into the blow pipe due to certain irregular conditions within the furnace or to faulty manipulation of the blast control. With an iron pipe which is bare interiorly it is usually possible to rod out the slag or iron which has chilled and partially 20 filled the pipe. If this is only a superficial filling 25 at the bottom of the pipe, the rodding out can be accomplished with the pipe in place and even with the blast on. In case of a brick lined pipe, however, the slag or iron will so cling to the 30 brick as to make its removal impossible without destroying the brick.

An object of the present invention is to provide an insulated blow pipe in which insulating material of high efficiency may be used and in which said insulating material is protected 35 against contact with slag or iron and also from the blast.

A further object is to provide an insulated blow pipe of high efficiency in which any slag or iron which may collect therein may be readily rodded 40 out.

A further object is to provide an insulated blow pipe in which the principal structural member is protected from the heat and operates at substantially lower temperature than the air blast.

45 A further object is to provide an insulated blow pipe in which the principal structural member is the exterior member and the insulation and the members exposed to heat are mechanically protected internal members.

50 A further object is to provide an insulated blow pipe which is simple to manufacture and which may be made at a relatively low cost.

A further object is to provide a blow pipe well 55 adapted to meet the needs of commercial opera-

Further objects will appear as the description proceeds.

Referring to the drawings:

Figure 1 is a view in side elevation, parts being broken away, illustrating a blow pipe embodying 5 the principles of the present invention;

Figure 2 shows a detail of construction, the parts being separated for simplicity of disclosure;

Figure 3 is a view similar to Figure 1 but illustrating another embodiment of the present invention which will probably be preferred by 10 some;

Figure 4 is a sectional view taken along the plane indicated by the arrows 4—4 of Figure 3;

Figure 5 shows a detail of construction; and

Figure 6 illustrates a detail of another modification.

Referring first to Figures 1 and 2, the numeral 10 indicates a pipe casing having the inturned annular portion 11 at one end thereof, which annular end portion provides the aperture 12 through which a hot blast of air may be directed to the tuyère of a blast furnace. The other end of the pipe casing 10 is internally screw-threaded for the reception of an externally threaded ring 13, the purpose of which will be referred to presently. Disposed in coaxial relationship with the pipe casing 10 is a cylindrical assembly, indicated as a whole by the numeral 14, which assembly is made up of the rings 15—15 which are 20 disposed end for end to provide said assembly 14. The rings 15—15 will be similar in size and contour, but one of them may be a short ring chosen of a length to make the assembly 14 correspond to the length of the pipe casing 10. The assembly 25 14 of said rings 15 is held in place at one end against the adjacent surface of the inturned portion 11 of the pipe casing 10 and at the other end by means of the threaded ring 13. The rings 15 may be chosen of a material which has ability to 30 withstand high temperatures without severe deterioration.

The rings 15 are jointed to each other and to the inturned end portion 11 by means of pipe joints, which are illustrated in Figure 2. It will 35 be noted that the material at one end of each ring 15 is thickened radially and is grooved, as indicated by the numeral 16, to receive the adjacent beveled edge 17 of the neighboring ring 15 or the beveled annular projection 18 of the 40 portion 11. The surface of contact axially of the assembly 14 between the beveled end 17 and the adjacent groove 16 is inclined in a direction toward the end portion 11 of the pipe casing, which 45 is the end which communicates with the tuyère. 50

According to the preferred construction, the material of the thickened end of each ring 15 should overlap the adjacent end of the neighboring ring 15 inwardly of said neighboring ring 15 in the manner illustrated in Figure 2. Correspondingly, the ring 15 adjacent to the tuyère end of the blow pipe should overlap the annular projection 17 inwardly thereof. Such overlapping portion is indicated by the numeral 19. By reason of this construction, a rod or chisel bar can be thrust into the ring assembly 14 from the stock end of the blow pipe, whereby iron or slag deposited within said assembly may be cleaned out without fouling the joints between the rings 15-15.

Surrounding the rings 15 is a packing of insulating material, indicated by the numeral 20. This insulating material may be chosen for its efficiency as an insulator, it being unnecessary to choose insulating material which is of itself capable of withstanding shocks or rough usage. Annular members 21-21 are provided between the inner surface of the pipe casing 10 and the thickened extremities of each of the rings 15-15 for the purpose of holding the ring assembly in its proper coaxial position within said pipe casing.

A preferred method of assembly of the structure disclosed in Figures 1 and 2 is as follows. The pipe sleeve 10 is disposed in a vertical position with the tuyère end thereof downward. The first sleeve 15 is mounted in place and the insulating material is placed between said first sleeve 15 and the pipe casing 10. When the space within the first ring 15 has been filled with insulating material, the next ring 15 is lowered into place in jointed relationship with the first ring 15. An annular member 21 is then dropped into place between the thickened end portion of said second ring 15 and the inner wall of the pipe casing 10. The next filling of insulation is applied in the same manner, and the sleeves, insulating material and annular members are progressively mounted in position until the blow pipe is assembled up to the stock end. Said annular members 21 act as struts to hold the ring assembly 14 against radial displacement relative to the pipe casing 10.

The screw-threaded ring 13 is provided with a groove 22 facing toward the tuyère end of the blow pipe adapted to receive and hold the adjacent end of the ring 15. Preferably a space is left in said annular groove 22 to allow for expansion of the ring assembly 14.

Referring now to the construction illustrated in Figures 3, 4 and 5, the pipe casing 10a takes a slightly different form from that illustrated in Figure 1. In the structure shown in Figures 3, 4, and 5, the arrangement and the form of the rings 15-15 is modified and another form of abutting means for holding the rings in coaxial relationship with the casing 10a is illustrated. In Figure 3 a slight modification is illustrated in the means for holding the rings in position axially of the device.

In the construction shown in Figures 3, 4, and 5 the casing 10a is provided at the tuyère end of the blow pipe with the inturned annular portion 11a, which annular portion provides an aperture through which a hot blast of air may be directed through the tuyère of the blast furnace. The other end of the pipe casing 10a is provided with the ring 13a, which fits within the pipe casing 10a and may be spot-welded to said pipe casing for the purpose of positioning the rings, which will now be described.

The numerals 15a-15a indicate rings or sleeves arranged end for end coaxially with respect to the pipe casing 10a, said rings 15a-15a being identical in contour except that one of said rings may be shorter than the others, whereby the length of the ring assembly may be chosen to correspond to any particular length of pipe casing. The assembly of the rings 15a is held in place at the tuyère end of the pipe casing 10a against the adjacent surface of the inturned portion 11a of said pipe casing, and the other end of said ring assembly is held in place by means of the ring 13a.

The rings 15a are jointed to each other and to the end portion 11 by means of pipe joints, which are illustrated on an enlarged scale in Figure 5. According to the structure illustrated in Figures 3 and 5, the material at one end of each ring 15a is thickened radially as indicated by the numeral 16a and is grooved internally. The other extremity of each of the rings 15a is of slightly less diameter than the diameter of the adjacent portion of its neighboring ring 15a. Likewise the ring 15a at the tuyère end of the blow pipe is of slightly less diameter than the adjacent portion of the inturned end 11 of the pipe casing 10a. The detailed view appearing in Figure 5 indicates the overlap at the tuyère end of each ring 15a and its neighboring ring and the overlap between the ring 15a at the tuyère end of the blow pipe and the adjacent portion of the inturned end 11a of the pipe casing 10a. Said overlap is indicated by the numeral 19a.

According to the structure illustrated in Figures 3 to 5, the means for holding the ring assembly 15a-15a in coaxial relationship with the pipe casing 10a is embodied in a plurality of bosses or lugs 21a-21a, which are disposed in abutting relationship with the thickened end portions of the rings or sleeves 15a-15a. Figure 4 illustrates three of these lugs or bosses 21a disposed substantially symmetrically around the inner circumference of the pipe casing 10a. In the construction shown in Figures 3 to 5, said bosses or lugs 21a are formed integrally with the pipe casing 10a.

The ring assembly 15a-15a is held in position longitudinally of the blow pipe by means of the ring 13a, which ring on the side thereof facing toward the tuyère end of the blow pipe is provided with the groove 22a, which is adapted to receive and hold the adjacent end of the neighboring ring 15a. As in the construction illustrated in Figures 1 and 2, a space is preferably left in said annular groove 22a to allow for expansion of the ring assembly 15a-15a.

Figure 6 illustrates another modification in which a sleeve 15b is provided which may be a unitary sleeve extending from one end to the other of the pipe casing 10a. Said sleeve 15b may be made up as preferred, a construction which is practical and feasible being to form a strip of suitable material into a tube providing a closed or a substantially closed sleeve from end to end. United to the exterior surface of the ring 15b is an abutment member indicated by the numeral 21b which may take the form of a ring, if preferred, extending around the periphery of the sleeve 15b or may take the form of a plurality of bosses or lugs disposed peripherally with respect to the sleeve 15b.

It will be understood of course that the details of construction from the three illustrated forms of the invention may be chosen as preferred in making up an assembly as, for example, the abutment means 21b of Figure 6 may be em-

bodied in either of the other two embodiments of the invention.

In the construction illustrated in Figure 6 it is practicable and feasible to build up the insulating material 20 upon a sleeve before said sleeve is placed in the pipe casing, any preferred means being used to hold said insulating material in place temporarily while the assembly is being slid into position. Or the insulating material 10 may be omitted altogether, the air space alone serving as the insulating means.

The blow pipe above described has the advantage that it may be readily assembled and is well adapted to withstand stresses to which it 15 may be subjected. Moreover said blow pipe is a self-contained unit with the lining definitely held in place at both ends. The insulating material 20 may be chosen as desired without regard to its resistance to the effect of slag or iron. The 20 rings 15 and 15a or the sleeve 15b may be chosen of an alloy which will resist the high temperature of the hot blast passing through it. By reason of the overlap 19 on each of the sleeves 15 and 15a, any deposit of slag or iron may be rodded 25 out without danger of fouling the joints between said rings 15—15, or between the rings 15a—15a, or between the tuyère end of the blow pipe and its neighboring ring. By reason of the conical 30 surface comprising the surface of contact between the rings, as disclosed in Figures 1 and 2, which conical surface tapers toward the tuyère end of the blow pipe, there will be very little tendency to push slag or iron into the space between the 35 ring assembly and the pipe casing when the ring assembly is being rodded out. Though it is preferred to use the heat insulating material in the space between the ring assembly and the pipe casing, certain advantages of the invention may 40 be attained without the use of said insulating material.

The present invention provides a structure in which the part of the blow pipe which provides structural strength, that is—the principal structural member, is insulated from the hot blast. 45 This construction has the two-fold advantage that (a) the stress-resisting member is never the hottest part of the blow pipe and therefore is able to preserve its strength-providing functions 50 unimpaired by extra high temperatures, and (b) the exterior of the blow pipe, being rugged, is well adapted to withstand the shocks to which blow pipes are commonly subjected when changes 55 must be made in or about the tuyère with which the blow pipe is associated.

Though a preferred embodiment of the present invention has been described in detail, many modifications will occur to those skilled in the art. It is intended to cover all such modifications that 60 fall within the scope of the appended claims.

What is claimed is:

1. In a blow pipe for blast furnaces, in combination, a pipe casing and a ring assembly within said casing, said ring assembly comprising a plurality of rings disposed end for end coaxially relative to said casing, each of said rings having an inwardly flaring end portion of less diameter than the remainder of said ring, most of said rings at their other ends having an annular shoulder for receiving and encircling the first mentioned end of an adjacent ring whereby said assembly may be cleaned out without fouling the joints between adjacent rings, and insulating material between said ring assembly and said casing, said rings being of a material capable of

resisting the high temperatures of a blast for blast furnaces.

2. In a blow pipe for blast furnaces, in combination, a pipe casing having an end portion, a ring assembly coaxially disposed within said pipe 5 casing, said ring assembly comprising a plurality of rings jointed together end for end and abutting longitudinally against said end portion of said pipe casing, and means at the other end of said pipe casing for holding said ring assembly relative to said pipe casing, said rings being of a material capable of resisting the high temperatures of a blast for blast furnaces.

3. In a blow pipe for blast furnaces, in combination, a pipe casing having an end portion, a 15 ring assembly coaxially disposed within said pipe casing, said ring assembly comprising a plurality of rings jointed together end for end and abutting longitudinally against said end portion of said pipe casing, means at the other end of said pipe 20 casing for holding said ring assembly relative to said pipe casing, and insulating material between said ring assembly and said pipe casing, said rings being of a material capable of resisting the high temperatures of a blast for blast 25 furnaces.

4. In a blow pipe for blast furnaces, in combination, a pipe casing having an end portion, a ring assembly coaxially disposed within said pipe casing, said ring assembly comprising a plurality of 30 rings jointed together end for end and abutting longitudinally against said end portion of said pipe casing, means at the other end of said pipe casing for holding said ring assembly relative to said pipe casing, and annular struts disposed 35 within said pipe casing and having abutting relationship with said rings for holding said ring assembly in fixed relationship to said pipe casing, said rings being of a material capable of resisting the high temperatures of a blast for blast furnaces. 40

5. In a blow pipe for blast furnaces, in combination, a pipe casing having an end portion, a ring assembly coaxially disposed within said pipe casing, said ring assembly comprising a plurality of 45 rings jointed together end for end and abutting longitudinally against said end portion of said pipe casing, means at the other end of said pipe casing for holding said ring assembly relative to said pipe casing, annular struts disposed within 50 said pipe casing and having abutting relationship with said rings for holding said ring assembly in fixed relationship to said pipe casing, and insulating material between said pipe casing and said ring assembly said rings being of a material capable of resisting the high temperatures of a 55 blast for blast furnaces.

6. In a blow pipe for blast furnaces, in combination, a pipe casing and a ring assembly coaxially disposed within said pipe casing, said ring assembly comprising a plurality of rings jointed together end for end, the inner periphery of each of said rings at the end thereof adjacent to the outlet of said blow pipe being flared inwardly and having overlapping relationship with the adjacent end of its neighboring ring in a direction toward 65 the axis of said ring assembly said rings being of a material capable of resisting the high temperatures of a blast for blast furnaces.

7. In a blow pipe for blast furnaces, in combination, a pipe casing and a ring assembly coaxially 70 disposed within said pipe casing, said ring assembly comprising a plurality of rings jointed together end for end, the inner periphery of each of said rings at the end thereof adjacent to the outlet of said blow pipe being flared inwardly and 75

- having overlapping relationship with the adjacent end of its neighboring ring in a direction toward the axis of said ring assembly, and means disposed at each end of said pipe casing for holding said ring assembly in a position substantially coaxially with said pipe casing said rings being of a material capable of resisting the high temperatures of a blast for blast furnaces.
8. In a blow pipe for blast furnaces, in combination, a pipe casing and a ring assembly coaxially disposed within said pipe casing, said ring assembly comprising a plurality of rings jointed together end for end, the inner periphery of each of said rings at the end thereof adjacent to the outlet of said blow pipe having overlapping relationship with the adjacent end of its neighboring ring in a direction toward the axis of said ring assembly, means disposed at each end of said pipe casing for holding said ring assembly in a position substantially coaxially with said pipe casing, and peripherally distributed means disposed outwardly of said rings and inwardly of said pipe casing for holding said ring assembly in substantially coaxial relationship with said pipe casing said rings being of a material capable of resisting the high temperatures of a blast for blast furnaces.
9. In a blow pipe for blast furnaces, in combination, a pipe casing having an end portion, a ring assembly coaxially disposed within said pipe casing, said ring assembly comprising a plurality of rings jointed together end for end and jointed to said end portion of said pipe casing, means at the other end of said pipe casing for holding said ring assembly relative to said pipe casing while permitting expansion of said ring assembly relative to said pipe casing and peripherally distributed means disposed outwardly of said rings and inwardly of said pipe casing for holding said ring assembly in substantially coaxial relationship with said pipe casing said rings being of a material capable of resisting the high temperatures of a blast for blast furnaces.
10. In a blow pipe for blast furnaces, in combination, a principal structural member comprising a pipe casing, a sleeve coaxially disposed within said casing, said sleeve being jointed to said pipe casing adjacent to the outlet end thereof and means carried by said casing at a region spaced from said outlet end and jointed to said sleeve for holding said sleeve in coaxial relationship with said pipe casing and insulating material between said sleeve and said pipe casing.
11. In a blow pipe for blast furnaces, in combination, a principal structural member comprising a pipe casing, a sleeve within said casing, means disposed peripherally with respect to said sleeve for holding said sleeve in coaxial relationship with said pipe casing said sleeve being of a material capable of resisting the high temperatures of a blast for blast furnaces, and insulating material between said pipe casing and said sleeve, said sleeve including layers disposed edgewise relative to each other.
12. In a blow pipe for blast furnaces, in combination, a pipe casing having an end portion, said pipe casing comprising the principal structural member of said blow pipe, a sleeve coaxially disposed within said pipe casing, means at the other end of said pipe casing for holding said sleeve in coaxial relationship with said pipe casing and insulating material between said pipe casing and said sleeve, said sleeve comprising a strip of material formed into a tube.
- end of said pipe casing for holding said sleeve relative to said pipe casing while permitting expansion or contraction of said sleeve relative to said pipe casing and peripherally disposed abutment means for holding mid-portions of said sleeve in coaxial relationship with said pipe casing, said rings being of a material capable of resisting the high temperatures of a blast for blast furnaces.
13. In a blow pipe for blast furnaces, in combination, a pipe casing having an end portion, a ring assembly coaxially disposed within said pipe casing, said ring assembly comprising a plurality of rings jointed together end for end and jointed to said end portion of said pipe casing, means at the other end of said pipe casing for holding said ring assembly relative to said pipe casing while permitting expansion or contraction of said sleeve relative to said pipe casing, and abutment means disposed within said pipe casing and having abutting relationship with said rings, said abutment means being disposed peripherally with respect to said ring assembly for holding said ring assembly in coaxial relationship with said pipe casing said rings being of a material capable of resisting the high temperatures of a blast for blast furnaces.
14. In a blow pipe for blast furnaces, in combination, a pipe casing having an end portion, a sleeve coaxially disposed within said pipe casing, said sleeve having abutting relationship longitudinally against said end portion and having its internal diameter adjacent to said end portion less than the internal diameter of said end portion said sleeve being of a material capable of resisting the high temperatures of a blast for blast furnaces.
15. In a blow pipe for blast furnaces, in combination, a pipe casing having an end portion, a sleeve coaxially disposed within said pipe casing and abutting against said end portion, means at the other end of said pipe casing for holding said sleeve relative to said pipe casing while permitting expansion or contraction of said sleeve relative to said pipe casing and insulating material between said pipe casing and said sleeve said sleeve being of a material capable of resisting the high temperatures of a blast for blast furnaces.
16. In a blow pipe for blast furnaces, in combination, a pipe casing having an end portion, a sleeve coaxially disposed within said pipe casing and abutting against said end portion, means at the other end of said pipe casing for holding said sleeve relative to said pipe casing and means disposed outwardly of said sleeve and inwardly of said pipe casing for holding mid-portions of said sleeve in substantially coaxial relationship with said pipe casing said sleeve being of a material capable of resisting the high temperatures of a blast for blast furnaces.
17. In a blow pipe, in combination, a principal structural member comprising a pipe casing, a sleeve within said casing, means disposed peripherally with respect to said sleeve for holding said sleeve in coaxial relationship with said pipe casing, and insulating material between said pipe casing and said sleeve, said sleeve comprising a strip of material formed into a tube.

OWEN R. RICE.

CERTIFICATE OF CORRECTION.

Patent No. 2,101,270.

December 7, 1937.

OWEN R. RICE.

It is hereby certified that error appears in the printed specification of the above numbered patent requiring correction as follows: Page 3, second column, line 30, claim 4, strike out the word "of"; page 4, first column, lines 66, 67 and 68, claim 12, strike out the words and comma "said pipe casing comprising the principal structural member of said blow pipe," and insert the same after the word and comma "portion," in second column, line 29, claim 14; and that the said Letters Patent should be read with these corrections therein that the same may conform to the record of the case in the Patent Office.

Signed and sealed this 22nd day of February, A. D. 1938.

Henry Van Arsdale,
Acting Commissioner of Patents.
